Primary Examiner — Michelle E. Wilson*Assistant Examiner* — Clese Moore, Jr.(74) *Attorney, Agent, or Firm* — Perkins IP Law Group LLC; Jefferson Perkins(57) **CLAIM**

The ornamental design for a floor mat connector, as shown and described.

DESCRIPTION

FIG. 1 is a perspective view of our design;

FIG. 2 is a top view thereof;

FIG. 3 is a bottom view thereof;

FIG. 4 is a front view thereof, a back view thereof being a mirror image of the front view; and,

FIG. 5 is a left side view thereof, a right side view being a mirror image of the left side view.

The broken lines shown illustrate environment that forms no part of the claimed design.

1 Claim, 4 Drawing Sheets(56)
